Des. 224,071

Patented June 27, 1972

224,071

COMBINED COMPACT AND COIN CONTAINER

Suvad Hatibovich, Murat Hot, and Rifat Hot, all of 26
Charles Veale Drive, West Beach, South Australia,
Australia

Term of patent 14 years

Filed May 6, 1970, Ser. No. 22,844

Int. Cl. D28—02

U.S. Cl. D86—10

FIG. 1 is a rear and top perspective view of a combined compact and coin container showing our new design in a closed position;

FIG. 2 is a side and bottom perspective view thereof;

FIG. 3 is a rear and bottom perspective view;

FIG. 4 is a front and top perspective view;

FIG. 5 is a front and left side perspective view of the design in an open position; and

FIG. 6 is a front end right side perspective view thereof.

We claim:

The ornamental design for a combined compact and coin container, as shown.
